UNITED STATES PATENT OFFICE

2,571,635

GARMENT HANGER

Edward G. Von Gunten, Akron, Ohio

Application December 8, 1948, Serial No. 64,199

1 Claim. (Cl. 223—88)

1

This invention relates to clothing hangers and particularly it relates to a hanger designed for women's clothing.

The hanger of this invention is primarily designed for the modern efficiency apartments and the smaller homes, hotels, etc. where closet space is usually very limited. In these places it is desirable to hang a number of garments on a single supporting means and thereby make the most effective use of the available space. It is also necessary to do this when packing trunks and the like. Conventional hangers are inadequate for holding a number of garments at the same time.

This hanger is adapted to hold a variety of different items of women's clothing at the same time and it will permit the individual removal of any garment of the group hanging thereon without interference from the remaining garments. The preferred hanger will support a woman's skirt, slip and upper over-garment such as a blouse or jacket. Any one of these may be removed from the hanger without disturbing the other two. The garments are freely suspended from the hanger so that they will not be wrinkled. There are no projections on the hanger that could cause injury to the garments. The device is simple, easily operated, and it is adjustable to accommodate various sizes. The parts of the hanger are preferably formed from a light-weight metal such as aluminum but a suitable plastic also may be used. The hanger is both ornamental and functional.

This hanger generally consists of two arms, one of which slides telescopically into the other. The outer arm is formed with inwardly turned flanges along its longitudinal edges. These flanges form a channel into which the inner arm is fitted. In a preferred form of the invention a spring is secured to the inside wall of this channel and it is adapted to press the inner arm against the flanges on which it slides. This spring holds these arms in frictional engagement with each other after they have been extended to a desired position. Suitable means are provided at the outer ends of the arms to hold the clothing and means for hooking the hanger to a hook or closet-rod is attached to the outer arm.

The invention will be more fully described by reference to the accompanying drawings in which—

Figure 1 is a side elevation of the preferred hanger;

Figure 2 is a bottom view of the center portion of the hanger;

2

Figure 3 is a view of the hanger in operative position;

Figure 4 is a detail view of the ends of the arms which are telescopically joined together and shows an alternate form of spring;

Figure 5 is a cross-sectional view of the modification shown in Figure 4 after assembly of the arms; and

Fig. 6 is a view of the right end of the hanger as shown in Fig. 1.

The cross member of this hanger consists of an outer arm 1 having flanges 2 formed along its longitudinal edges. These flanges 2 are preferably slightly curved and directed toward each other to form a channel. An inner arm 3, is bowed in cross section, or if a solid the cross section is a segment. It is adapted to be inserted into this channel so that its convex side is in contact with the curved flanges 2.

A flat spring 5 is riveted near the end of the outer arm 1 on the side of it forming the interior wall of the channel. The spring 5 is adapted to exert pressure on the inner arm 3 when it is telescopically engaged with arm 1. This spring 25 5 presses the arm 3 against the flanges 2. It will allow the inner arm 3 to be slid into and out of the channel but it is of sufficient strength to hold the inner arm 3 in frictional engagement with the inside surface of the flanges 2 when the arm 3 has been extended to some desired position.

Plates 8 are attached to one end of each of the telescoping arms 1 and 3. The plates 8 receive the garments that are to be hung on the hanger and various portions of the plates 8 are shaped to receive a specific garment.

The portion 9 of plates 8 are adapted to receive the waist-band of a skirt 10. Each portion 9 slants outwardly from the body of the hanger 40 and terminates in the rounded knob 11. A skirt 10 may be placed on the hanger by extending the telescoping arms 1 and 3 until the portions 9 of both plates 8 are in contact with the inside of the waist-band. The knobs 11 prevent the 45 waist-band from slipping off the portions 9. As described above, the spring 5 will lock the arms 1 and 3 at any position to which they are adjusted thereby tensioning the waist-band and holding the skirt thereon.

Notches 12 are provided on the upper, inward edges of the plates 8 to receive the shoulder straps of a slip 13. A slip 13 is hung on this hanger in the manner shown in Figure 4, the body of the slip 13 being on the outside of the skirt 10.

The upper edges 15 of plates 8 are curved to receive the inner sides of the shoulder portions of a blouse or jacket 16 which is hung thereon in the manner shown in Figure 4.

Any of these garments may be easily removed without disturbing the others. For example, if it is necessary to remove the skirt 10 only, the arm 3 is retracted into the arm 1, until the tension on the waist-band is relieved. The skirt 10 will then drop out from under the jacket 16. The slip 13 or the jacket 16 may be removed without changing the relative positions of the arms.

A suitable hooking means 18 to engage the hanger with a closet-rod is secured to the outer arm 1 in a manner that will not interfere with the telescoping action of arm 3. The preferred means 18 is a bird-like figure with the portion 19 under the head of the bird being formed to fit over a supporting rod on which the hanger will be hung. The hook 18 and the portion 19 of it are positioned at points necessary to give the hanger proper balance.

The plates 8 may be of any suitable shape to accommodate the garments which will be hung thereon.

Any means for frictionally engaging the arm may be employed. Figures 5 and 6 show a modified structure in which a wire spring 20 is used for this purpose. The spring is fastened to the outer arm 21. The inner arm 22 is curved in cross section and provided with a groove 23 in which the spring is guided.

The various members of the hanger may be inexpensively stamped or extruded from metal or they may be molded from a suitable plastic. They are preferably riveted together if of metal.

5 What I claim is:

A hanger for supporting a plurality of garments at the same time comprising an outer and an inner arm, the inner arm being telescopically slidable with respect to the outer arm and two substantially flat plates secured to the outer ends of the respective telescoping arms, each plate having a lower portion slanting downwardly and outwardly to receive the waist-band of a skirt when the arms have been sufficiently extended, an edge curving upwardly and inwardly above the arm to receive the interior side of the shoulder section of an upper outer-garment, and a notch on the upper edge to receive a strap of a slip.
